UNITED STATES PATENT OFFICE

140,417

DESIGN FOR A MAGICIAN'S TRICK DEVICE

Kenneth S. Franke, Woodside, N. Y.

Substituted for abandoned application Serial No. 110,319, May 28, 1943. This application March 9, 1944, Serial No. 112,831

Term of patent 3½ years

(Cl. D34—5)

To all whom it may concern:

Be it known that I, Kenneth S. Franke, a citizen of the United States, residing at Woodside, in the county of Queens and State of New York, have invented a new, original, and ornamental Design for Magician's Trick Device, of which the following is a specification, reference being had to the accompanying drawing, forming a part thereof. This application is a substitute for an abandoned application Serial No. D-110,319 filed May 28, 1943.

In the drawing,

I claim:

The ornamental design for a magician's trick device, as shown.

KENNETH S. FRANKE.
